UNITED STATES PATENT OFFICE.

GEORGE E. GILMAN, OF WEST NEWBURY, MASSACHUSETTS.

CURTAIN-FIXTURE FOR OPEN CARS.

No. 884,480.

Specification of Letters Patent.

Patented April 14, 1908.

Application filed October 29, 1907. Serial No. 399,710.

To all whom it may concern:

Be it known that I, GEORGE E. GILMAN, a citizen of the United States, residing at West Newbury, in the county of Essex and State 5 of Massachusetts, have invented certain new and useful Improvements in Curtain-Fixtures for Open Cars, of which the following is a specification.

This invention relates to railway cars and 10 particularly to curtain fixtures which are especially adapted for use between the side posts of that type of cars commonly known as "open street cars".

To this end the invention particularly has 15 in view the provision of certain novel and practical improvements upon the construction of curtain fixture for cars disclosed and covered by my former patent No. 787,841. In this connection, the invention contem- 20 plates an improved construction which insures the better working of the curtain, not only as to the matter of the guiding thereof between the side posts, but also as to its retention in any adjusted position so as to prevent 25 the displacement thereof from such position by heavy vibration or jars.

With these and other objects in view which will more readily appear to those familiar with the art, the invention consists in the 30 novel construction, combination, and arrangement of parts hereinafter more fully described, illustrated and claimed.

In the accompanying drawings, which exemplify the preferred embodiment of the 35 improvement, Figure 1 is a side elevation of a portion of an open street car equipped with a curtain fixture embodying the present invention. Fig. 2 is an enlarged sectional view of the lower end portion of one of the side posts 40 and the lower end portion of the curtain and its base board, illustrating more fully the operative positions and mounting of the sliding catch springs and the extension guide brackets. Fig. 3 is an enlarged sectional view 45 of the bottom edge portion of the curtain taken on the section line 3—3 of Fig. 1. Fig. 4 is a detail cross sectional view of one of the side posts of the car body.

Like references designate corresponding 50 parts in the several figures of the drawings.

As indicated in the former patent aforesaid, the improvements contemplated herein are applicable to any of the ordinary types of open street cars embodying in their organization, as shown in the drawings, the floor 1, a 55 roof section 2, the transversely arranged

seats 3, and a series of upright side posts 4, extending from the floor to the said roof section, and which side posts are arranged at the ends of the seats.

60

A feature of the present invention resides in constructing the side posts 4 so as to extend down to and preferably below the plane of the floor 1 and also arranging said side posts in a plane wholly outside of the ends of 65 the seats and the supports therefor. Furthermore, the side posts are formed in their opposing edges with deep guiding grooves 5 extending longitudinally from end to end of the post and slidably receiving therein the 70 opposite side edges of the flexible curtain body 6, which is designed to cover and uncover the passageway provided for between the opposing side posts.

The curtain body made up of the usual 75 flexible sheet portion is arranged to wind and unwind upon an ordinary type of spring actuated roller 7 mounted in suitable hangers within the roof section 2 of the car body, said roller subserving its ordinary function of providing a lifting means for the curtain to facilitate the raising thereof. One of the practical parts of the curtain fixture is the equipment of the curtain body at its bottom edge 80 with a wide base board 8 constituting the 85 bottom section of the curtain. This base board 8 is designed to be connected with the bottom edge of the curtain body by means of any suitable thoroughly weatherproof connection 9 such as described and illustrated 90 in my former patent, but irrespective of the character of the connection 9, it will, of course, be understood that the base board may be constructed of any desired or necessary width and may be formed either solid 95 or hollow. Also, the said board is preferably fitted with the inner and outer lifting buttons 10 and 11 respectively, and also has projected from its inner side a stop pin 12 adapted to engage with the floor of the car 100 when the curtain is entirely lowered. When in such position, the base board overlaps and projects a material distance below the level of the floor 1, thus providing an effective weatherboard which excludes wind and rain. 105

As shown in the drawings, the ends of the base board 8 project into and slide within the guiding groove 5 of the opposing side posts 4, and in order to secure an effective and steady guiding of the board in the said 110 groove 5 at all times and under all conditions, the present invention contemplates fitting

the said board at its opposite ends with extension guide brackets 13. These brackets are preferably arranged at the bottom corners of the base board and each consists essentially of an angle iron having a horizontal attaching arm 14 secured by bolts or rivets 15, or equivalent fastening means, to the body of the base board, and a pendent slide arm 16 projecting a material distance below the bottom edge of the base board and sliding within the grooves 5. Also, each end of the base board 8 is fitted with a sliding catch spring 17 having a rounded engaging end 18 slidably interlocking with the depressions or seats of a corrugated keeper bar or strip 19 seated in the bottom of the guiding groove 5 receiving said spring. Each groove 5 is similarly equipped with a bar 18.

In the preferable construction shown, the base board 8 is of hollow formation, and may be of either metal or wood. When of hollow formation, the arms 14 of the extension guide brackets are inserted within the open ends of the base board, and the fast ends of the spring 17 may be conveniently secured upon the said arms 14 by the fastenings 15. The slide arms 16 of the brackets extend the effective guiding bearing for the ends of the base board, while the springs 17 and strips 18 check and hold the curtain against displacement from any adjusted position.

In carrying out the invention it will be noted that minor details in the form, propor-

tion and arrangement of the parts may be resorted to without departing from the spirit of the invention, such for instance as arranging the curtain to operate inside as well as outside of the ends of the seats; and, also without departing from the invention, it will be understood that the extension guide brackets 13 may be secured in different positions and different ways to the base board so long as the necessary operative relation is preserved to the corrugated keeper bar or strip 19. Other similar variations may be resorted to without sacrificing any of the advantages of the invention.

I claim:

In a curtain fixture for cars, the car body having side posts provided with guiding grooves and corrugated keeper bars therein, a flexible curtain carrying at its bottom edge a rigid base board, angle extension guide brackets having horizontal attaching arms disposed within the ends of the base board, and catch springs slidably interlocking with the corrugations of the keeper bars and secured to the base board by the fastenings for the attaching arms of said angle brackets.

In testimony whereof I hereunto affix my signature in the presence of two witnesses.

GEORGE E. GILMAN.
